GRAIN CLEANING DEVICE

Monroe Davis, Blackwell, Okla.

Application December 26, 1930, Serial No. 504,803

4 Claims. (Cl. 209—138)

This invention relates to grain cleaners.

The object of the invention is to provide a cleaner in which the grain is cleaned by falling and striking obstructions and coming in contact with a draft of air traveling in the opposite direction from the falling grain.

Another object is to provide a grain cleaner as above described and having a means of adjusting the size of the stream of grain flowing

10. through the cleaner.

Another object is to provide a cleaner of the kind described having a plurality of obstructions positioned in the line of travel of the flowing grain.

15. These and other objects will be more fully explained as this description progresses.

Referring to the drawing, Fig. 1 is a side view of the device. Fig. 2 is an enlarged detail sectional view of the working parts of the device.

20. Fig. 3 is a plan view of Fig. 2. Fig. 4 is a cross

sectional view, taken on the line IV—IV in Fig.

2. Fig. 5 is a cross sectional view taken along

the line V—V in Fig. 2. Fig. 6 is a cross

sectional view taken along the line VI—VI in Fig.

25. 2. Fig. 7 is a rear view of the dirt trap.

In the drawing is shown a funnel shaped hopper element 10 having a depending tube 11, said tube 11 having an enlarged portion 12, from

30. the tube 11 is a larger tube 14 having an air

tight connection with the funnel portion of the

35. hopper 10. Just below the element 12 the tube

decreases in diameter as shown at 15 and joins

with an air tight joint to a smaller perpendicular

30. tube 16 which incloses the perpendicular tube

13, leaving an air space between the tubes 13

and 16. At 17 is a rod positioned on the center

40. axis of the elements previously described and

slidably held in guides 18 and 19 which are sup-

ported by spider arms 20 and 21 attached to the

sidewalls of the tube 11 and the hopper 10 as

shown. At 22 are shown spacing elements be-

tween the walls of the tubes 11 and 14 as a means

of retaining the tubes 11, 13, and 14 and the

45. rods 17, all on the same center axis. At 23 is

a rocker arm pivotally mounted at 24 on a sup-

porting element 25, the inner end of said arm

23 being bifurcated and the bifurcated portions

being provided with a slot 26 in which is re-

50. tained a pin 27 which is rigid with the upper

end of the rod 17. At 28 is a support bracket,

supporting a spring 29 and functions to raise the

outer end of the lever 23 and drop the inner end

of said lever, thereby causing the rod 17 to be

55. actuated up or down as the case may be.

On the outer end of the lever 23 is attached a wire or cable 30 which hangs therefrom, the lower end of said cable 30 is attached to a lever arm 31, which is pivotally mounted at 32 to any suitable element 33. The outer end of the arm 31 is provided with a worm gear segment 34 which is in engagement with a worm 35 held in bearings 36 and 37 mounted on the element 33. Integral with the worm 35 is a depending shaft 37 which is provided with a crank 38 having a handle 39 with which to turn the crank. On the lower end of the rod 17 is a cone shaped element rigidly mounted on the shaft 17 and being slightly larger in diameter than the tube 13, so that when the element 40 is moved downward toward the upper end of the tube 13, it will function as a valve to open or close the tube 13 to admit or deny the passage of any material which may be in the tube 11. This valve may also be adjusted to admit the passage of any desired amount of material in the tube 11 to the tube 13.

At 41 is an enlarged tubular element having an air tight connection 42 with the tube 16; the lower end of the tube 41 also having an air tight connection 43 with the perpendicular tube 44 which is smaller in diameter than the tube 41. Housed within the tube 41 is a tubular element 45, said tubular element 45 being smaller in diameter than the tube 41 and being provided with a funnel shaped portion 46 on the upper end thereof; the lower end of the tube 45 being decreased in diameter and terminating with a short pipe 47. Within the pipe 45 is a cup element 48 which is supported by supporting arms 49, spanning the space between the walls of the tube 45 and the cup 48. The tube 45 is rigidly held in axial alignment with the tube 41 by supporting arms 50 and 51 spanning between the walls of the tubes 45 and 41.

At 51 is a tubular element larger in diameter than the pipe 44, and having an air tight connection with the tube 44 by means of the cone shaped element 52; the lower end of the element 51 being decreased in diameter as shown 45 at 53 and having an air tight connection to the tubular element 54; axially positioned within the tubular element 55 which is smaller in diameter than the element 51 and being supported in said element 51 by support arms 56 and 57, 50 which span between the side walls of the tubular elements 51 and 55; the upper end of the element 55 being provided with a funnel shaped portion 58. The lower end of the tube 55 being decreased in diameter and terminating with a 55

short tubular element 59, centrally positioned within the tube 54. Axially positioned within the tubular element 55 is a double cone shaped element 77, supported within the tube 55 by means of supporting arms 78 spanning between the elements 77 and the walls of the tubular element 55. The lower end of the tube 54 is provided with a plurality of rows of air holes or openings 60 and 61. At 62 and 63 are shown funnel shaped elements tightly fitting and rigidly attached to the tube 54 at a point just below the rows of holes 60 and 61, the lower end of the tube 54 being decreased in diameter and terminating in a smaller pipe element 64, to which may be attached any suitable spouting element (which is not shown). At 65 is a horizontal tubular element opening into the tubular element 14, the horizontal tubular element 65 bending downward as shown at 66 and continuing as pipe 65' to, and connecting with a blower 67. Depending from, and opening into the horizontal tubular element 65 is a perpendicular tube, terminating in a box or dirt trap 69, comprising a box like inclosure having an intermediate division 70 therein, supporting a hinged door element 71 adapted to contact the bottom 72 of the enclosure. At the lower end of the rear wall 73 is provided a hinged door element 74 which is adapted to contact the bottom 72 and side walls 30 of the enclosure 69, the object of which will be later explained. At 76 is a raised element in the lower side of the pipe 65, positioned adjacent the opening of the pipe 68 into the pipe 65 and between the junction of the pipes 65 and 68 and 35 the elements 65 and 14.

In Fig. 1 at 75 is shown a spout through which grain may be fed or supplied to the hopper 10.

The operation of my grain cleaner is as follows: The valve 40 may be closed by operating the crank 38 so as to allow the spring 29 to tilt the inner end of the lever 23 downward so that the cone 40 contacts the element 12 to close the passage. Then grain is fed through the spout 75 into the hopper 10 filling the tube 11 and the hopper 10. The blower 67 being driven by any suitable source of power (not shown), draws air in through the openings 60 and 61, and draws it up through all the tubular elements thereabove into the pipes 65 and 65' and discharges it from the blower in the direction of the arrow A. The air in passing through the tubular element 65 strikes the element 76 causing an air eddy and vacuum over the opening into the pipe 68.

Now by turning the crank 38 the valve 40 is adjustably opened to admit the desired amount of grain and dirt therewith to fall therethrough, the grain traveling in a downward direction within an upwardly traveling draft of air which will pick up such light particles of dirt contained within the stream of grain flow and carry the dirt upward with the air, allowing the heavier grain to strike the funnel element 46 and be discharged into the cup element 48, thereby filling the cup, allowing the oncoming grain to beat against that in the cup and overflow around the sides of the cup and fall through the tubular element 47, into the tube 44. During this process, dirt or chaff which may have been attached to the grain has been beaten off and is separated from the grain and is falling in the grain stream within the tube 44 where the grain stream again comes in contact with the upwardly traveling draft of air and the lighter elements such as the dust, chaff, and even the light

er kernels of grain which are of no value will be caught in the air stream and carried upward to the tube 65. The balance of the grain in the grain stream, falling downward through the tube 44 into the funnel 58 and onto the upper side of the cone element 77 where it is deflected against the side walls of the tube 55 and finally discharged through the tube 59 into the tube 54 and during the travel of the grain through the funnel 58 and tube 55, any additional dirt and the like still remaining on the grain has become loosened and separated from the grain during its travel through the funnel 58 and tube 55 is caught in the upwardly traveling air stream which has entered the pipe 54 through the openings 60 and 61 and said dirt, chaff, etc., is carried upwardly with the air stream into the pipe 65 and the remaining grain traveling downward is discharged through the pipe 64 into any suitable means (which is not shown) to any desired 20 car, bin or other place.

During the downward travel of the stream of grain in the tube 54, it may be that some of the kernels would enter the holes 60 or 61 and if they did they would be led back into the pipe 25 54 through the openings 60 or 61 by reason of the funnel shaped elements 62 or 63.

During the time the grain is falling from top to bottom of the cleaner, the heavier kernels of the grain will fall faster than the lighter ones and also the dirt in the grain stream, thereby crowding the dirt and lighter kernels of grain to the outside of the grain stream where it comes in contact with the upwardly traveling air stream and is picked up by the air and taken along with it. During the flow of the air through the pipe 65, the air will contact the upwardly projecting element 76 and cause an air eddy and vacuum over the opening of the pipe 68, and due to this action, such objects as light grain and the heavier portions of dirt that may be in the air stream will fall into the tube 68, and be deposited in the box 69, while the balance of the air and dirt will travel through the pipe 65' and the blower 67 and be deposited in the box 69, while the balance of the air and dirt will travel through the pipe 65' and the blower 67 and be discharged therefrom in the direction of the arrow A. The dirt and light grain which has been deposited in the box 69 will slide down the division 70 in the door 71 and the bottom 72 and be deposited between the bottom 72 and the door 72, and when enough dirt piles up against the door 72 its weight will push the door open in the direction of the arrow B and allow the dirt to be discharged from the box 69, and upon the opening of the door 74, air will be admitted to the box 69 and the pressure of the air against the door 71 will cause the door 71 to close while the dirt is discharging through the door 74 and when the dirt has all been discharged the door 74 will close by gravity and the air pressure against the door 71 will decrease and the door 71 will open by gravity, allowing the newly collected dirt, etc., to slide down the floor 72 against the door whereupon the opening and closing of the doors 74 and 71 are repeated.

Such modifications may be employed as lie within the scope of the appended claims without departing from the spirit and intent of my invention. Now having fully described my invention, what I claim as new and desire to secure by Letters Patent is:

1. In a grain cleaning device of the kind de- 75

scribed, a hollow vertical tube, said hollow vertical tube having enlargements therein at spaced intervals, obstructions in said vertical tube, said obstructions being positioned in said enlargements in said vertical tube, air intake openings in the walls and at the lower end of said vertical tube and a discharge opening at the bottom of said vertical tube, a hopper on the top of said vertical tube and means in said hopper to control the discharge from said hopper into said vertical tube, and means for drawing air in at the bottom of said vertical tube and discharging it at the top thereof as and for the purpose described.

2. In a grain cleaning device of the kind described, the combination of a hollow vertical tube, said hollow vertical tube having a plurality of enlargements therein, a hopper positioned at the top of said hollow vertical tube and discharging therein, means for controlling the discharge from said hopper, obstructions in said enlargements, said obstructions being positioned in line with the stream being discharged from said hopper, said obstructions functioning to spread and collect the stream being discharged from said hopper so that the material in said stream will beat against itself and the walls of said obstructions, openings in the walls of and at the bottom of said hollow vertical tube to admit air to said hollow vertical tube, a horizontal tube at the top of and one end communicating with the said hollow vertical tube, the other end being connected to an air fan functioning to draw air in at the bottom of the said hollow vertical tube and discharge it at the top thereof through said horizontal tube, a second vertical tube connecting with and depending from the said second vertical tube, all functioning as and for the purpose described.

3. In a grain cleaning device of the kind described, the combination of a hollow vertical tube, said hollow vertical tube having a plurality of enlargements therein, a hopper positioned at the top of said hollow vertical tube and discharging therein, means for controlling the discharge from said hopper, obstructions in said enlargements, said obstructions being positioned in line with the

stream being discharged from said hopper, said obstructions functioning to spread and collect the stream being discharged from said hopper so that the material in said stream will beat against itself and the walls of said obstructions, means at the bottom of said hollow vertical tube to admit air to said hollow vertical tube, a horizontal tube at the top of said vertical tube, one end of said horizontal tube being connected to the said vertical tube, the opposite end of said horizontal tube leading to and being connected to an air fan functioning to draw air in at the bottom of said hollow vertical tube and discharge it at the top thereof through said horizontal tube, a second vertical tube connecting with and depending from the said horizontal tube, and a dust trap positioned on and at the bottom of said second vertical tube, all functioning as and for the purpose described.

4. In a grain cleaning device of the kind described, a hollow vertical tube, said hollow vertical tube having enlargements therein at spaced intervals, obstructions in said vertical tube, said obstructions being positioned in said enlargements, means at the bottom of said hollow vertical tube to admit air therein, a horizontal tubular element at the top portion of, and connecting with the said vertical tube, a hopper on the top of said vertical tube and means in said hopper to control the discharge from said hopper into said vertical tube, a second vertical tubular element connecting to and depending from said horizontal tubular element, an upwardly projecting element in said horizontal tubular element at the junction of said horizontal tubular element and the second said vertical tubular element and between the first said vertical tube and the second said vertical tubular element, a dust trap on the lower end of said second vertical tubular element, and means for drawing air in at the bottom of the first said vertical tube and discharging the air through the horizontal tubular element substantially as described and for the purpose set forth.

MONROE DAVIS. 45
